UNITED STATES PATENT OFFICE

PHILIP A. JACKSON, OF DAYTON, OHIO

AUTOGRAPHIC REGISTER

Application filed April 13, 1931. Serial No. 529,604.

This invention relates to autographic registers and more particularly to that type of register in which the web consists of a pad of connected forms folded in superimposed relation.

One object of the invention is to provide such a register in which the final position of the web with relation to the severing device will be controlled by a crease between adjacent forms or sections of the web.

A further object of the invention is to provide such a register in which the feeding members will serve both to advance the web and to clamp the same against movement after the feeding operation has been completed and in which the positioning of the web will be effected by a crease between adjacent sections thereof between the feeding and clamping operations.

A further object of the invention is to provide such a register in which both the releasing of the web and the positioning thereof will be controlled by the crease in the web.

A further object of the invention is to provide a register of this kind in which the web will be advanced a predetermined distance by the feeding mechanism and the final positioning of the web will be determined by a crease in the web.

A further object of the invention is to provide a register of this kind in which a plurality of superimposed webs will be maintained in alinement.

Other objects of the invention will appear as the mechanism is described in detail.

In the accompanying drawings Fig. 1 is a plan view, partly broken away, of a register embodying my invention; Fig. 2 is a longitudinal sectional view of such a register; Fig. 3 is a section taken on the line 3-3 of Fig. 2; Fig. 4 is a section taken on the line 4-4 of Fig. 2; Fig. 5 is a section taken through the web guide, on an exaggerated scale, and showing one position of the web with relation to the guide; Fig. 6 is a similar view showing another position of the web with relation to the guide; Fig. 7 is a longitudinal sectional view, partly broken away, of a modified form of the invention; Fig. 8 is a plan view of the feeding and positioning

mechanism shown in Fig. 7; Fig. 9 is a section taken through the guide showing one position of the web with relation thereto; and Fig. 10 is a similar view showing another position of the web with relation to the guide. 55

In these drawings I have illustrated two embodiments of my invention but it will be understood that these particular embodiments have been chosen for the purposes of illustration and the mechanism may take 60 various forms without departing from the spirit of the invention.

In both forms here illustrated the register comprises a supporting structure or housing 10 having means for supporting 65 therein a web of paper or the like folded into sections of form length, as shown at 11. Creases are formed between adjacent sections of the web by weakening the web along transverse lines in a well known manner, as 70 by scoring the same or by a line of small perforations, which will permit each section to fold in either direction with relation to an adjacent section. The top wall 12 of the housing is provided with a writing opening 75 beneath which is arranged a writing table 13. Arranged beyond the writing table is a feeding mechanism which preferably comprises a lower feeding roller 14 mounted on a fixed axis within the housing and an upper 80 feeding roller 15 yieldably supported above the roller 14 so that it may be moved into and out of operative engagement with a web resting upon the lower roller. The rollers are provided at each end thereof with 85 cylindrical portions 16, preferably of reduced diameter and adapted to receive between them tapered members 17 by means of which the upper roller may be elevated to release the web. Arranged beyond the feeding 90 rollers is means for severing the discharged portions or forms of the web, which is here shown as a cutting edge 18.

The web is carried from the stack of forms or pad, as shown in Fig. 2, about a guide, 95 here shown as a roller 19, which is arranged near the rear end of the register just below the top wall thereof. Preferably a supporting roller 20 is arranged below and forwardly of the guide roller 19 to support the web 100

in substantially horizontal position below the guide roller. The web is carried forwardly from the guide roller above the writing table 13 to the feed rollers. These 5 rollers may be actuated in any suitable manner. As here shown, they are connected one to the other for rotation in unison by means of a gear 21 on the roller 15 and a gear 22 on the roller 14. The gear 22 meshes with a large 10 gear 23 rotatably mounted on a stud shaft 24 journaled in the side wall of the housing. Rigidly secured to the outer end of this stud shaft is an operating handle 25 and rigidly secured to the stud 24 within the housing is 15 a pawl carrier 26, here shown as a segmental plate, on which is supported a spring actuated pawl 27 which engages with a ratchet wheel 28 loosely mounted on the stud and rigidly connected with the gear 23. The operating 20 handle is supported in its normal position by a stop 29 and is moved rearwardly to impart movement to the feeding rollers through the pawl and ratchet mechanism. The gear ratio is preferably such 25 that a single movement of the operating handle will advance the web a distance equal to the length of the longest form which the machine is capable of handling.

When the web has been advanced the desired 30 distance it is released from the feeding mechanism, accurately positioned with relation to the edge 18 and then again engaged by the feeding mechanism which then serves to clamp the same against movement. These 35 operations may be effected in various ways but, as shown in Figs. 1 to 3, the tapered member 17, which serve to separate the feeding rollers and release the web, are tapered rearwardly and they are connected at their rear 40 ends by a transverse bar or plate 30 to one end of which is secured a bar 31 which is slidably mounted in guides 32 on the adjacent side wall of the housing to hold the bar 30 against twisting movement and to cause the tapered 45 members to move in unison. The tapered members are normally supported in a retracted position in which they will not interfere with the operative engagement of the upper roller with the web. Connected with 50 the plate 30 is a rearwardly extending arm 33 which is pivotally connected at its rear end with an arm 34 rotatably mounted on the stud shaft 24. The arm 34 is normally stationary but means are provided for imparting 55 rearward movement thereto when the web has been advanced the desired distance, thereby releasing the web from the feeding members. For this purpose I have provided the pawl carrying plate 26 with a stop, such as 60 a pin 36, arranged to engage the edge of the arm 34 and cause the same to move with the shaft and thus draw the tapered members between the rollers. The movement imparted to the web by the feeding mechanism preferably 65 advances the same a distance slightly

in excess of that required to properly position the form with relation to the severing edge 18. The guide roller 19 is spaced from the cutting edge such a distance that a crease between adjacent web sections will be in contact with the guide roller at the time that the web is released by the feeding members and the web will tend to move or spring rearwardly, due to the resiliency of the paper and the position of the crease with relation to the guide roller, as shown in Fig. 6. It will be noted that the roller 20 supports the lower portion of the web substantially parallel with the upper portion thereof, thus causing the web to bend sharply about the guide 19 and placing the same under such tension that the resiliency of the web will cause the creased portion thereof to spring rearwardly. This rearward movement is checked by a suitable stop, such as a plate 37 arranged in the rear of the guide roller. This stop plate is spaced from the cutting edge a distance exactly equal to the length of one form or of a plurality of shorter forms and when a crease in the web is in engagement with the stop plate a preceding crease will be properly positioned with relation to the severing edge 18. This positioning of the web takes place instantly upon the releasing of the webs from the feeding members and upon the return of the actuating handle to its normal or initial position a stop or pin 38 on the pawl arm 26 will engage the rear edge of the arm 34 and move the tapered members forwardly so as to permit the upper roller to again engage the web and thus clamp the same against movement. The rearward movement which is imparted to the creased portion of the web as it passes about the guide serves to maintain the plurality of webs with their forms in alinement, this being due to the forcing of the crease in each lower web into the crease in an upper web. The distance which the web is advanced upon each operation of the feeding mechanism may be varied by adjusting the stop 36 with relation to the plate 26, the latter being provided with a series of holes 39 in any one of which the stop 36 may be inserted. Means are preferably provided whereby the rollers 100 19 and 20 and the stop plate 37 may be adjusted with relation to the supporting structure or housing to correspond to the adjusted position of the stop 36 and for this purpose the housing is provided with a plurality of bearing openings 40 and slots 41 to support the rollers and plate in adjusted positions.

In Figs. 7 and 8 I have illustrated a modified form of the register in which the releasing of the web by the feeding members is controlled by the crease in the web. As here shown, the feeding rollers and their operating mechanism are similar to those above described but the tapered members 42, which separate the feeding rollers, are tapered forwardly and the plate 43 to which those tap-

ered members are connected has a rearwardly extending arm 44 pivotally connected at its rear end with an upright lever 45 pivotally supported at its lower end, as shown at 46, 5 Connected with this lever between its ends is a rod 47 the rear end of which is pivotally connected to the lower end of a lever 48 pivoted between its ends, as shown at 49, and having its upper portion arranged to the rear 10 of and adjacent to the guide roller 19. The parts are so mounted and balanced that a very light pressure on the upper end of the lever 48 will be sufficient to move the tapered members 42 into frictional contact with the feed rollers, 15 which will then draw the tapered members forwardly and cause them to separate the two rollers. As the crease in the web passes about the guide roller 19 it will assume a position somewhat similar to that shown in 20 Fig. 9 because the rear end of the preceding section of the web will tend to spring outwardly and to draw with it the forward edge of the following section. This will cause the crease in the web, which connects the two 25 sections, to contact with the lever 48 and move the upper end thereof rearwardly, thereby actuating the lever 45 and moving the tapered members into engagement with the rollers, which results in the web being released from 30 the rollers. The continued movement of the handle 25, after the web has been released, will cause a stop or pin 50 on the pawl carrying plate to engage a projection 51 on the bar 44 and retract the tapered members 42, 35 thus permitting the rollers to again grip the web and restoring the lever 48 to its normal position. The contact of the lever 48 with the web will impart a slight forward movement to the latter but the rollers being in 40 motion at the instant they grip the web will advance the forward end of the web a like distance and the web will be maintained taut and will be held against movement after the rotation of the rollers has been stopped by the 45 engagement of the handle with a stop 52.

While I have shown and described certain embodiments of my invention I wish it to be understood that I do not desire to be limited to the details thereof as various modifications 50 may occur to a person skilled in the art.

Having now fully described my invention, what I claim as new and desire to secure by Letters Patent, is:

1. In an autographic register comprising a 55 structure adapted to support a web of paper which is folded into superimposed sections of equal length, feeding mechanism comprising a pair of rollers, one of which is movable toward and from the other, a gear connected with said rollers, pawl and ratchet mechanism for actuating said gear, an operating handle connected with said pawl and ratchet mechanism, means connected with said operating handle to cause said movable feeding 60 roller to be moved to an inoperative position

when a predetermined movement has been imparted to said handle and to restore said feed roller to its operative position when said handle is moved in the opposite direction, a guide for said web so arranged that a crease between adjacent sections of said web will be in engagement therewith when said feed roller is moved to its inoperative position and the resiliency of said web will move the same rearwardly, and means for limiting the rearward movement of said web. 70

2. In an autographic register comprising a structure adapted to support a web of paper which is folded into superimposed sections of equal length, a pair of feeding rollers one of which is movable toward and from the other, a shaft, a gear rotatably mounted on said shaft and operatively connected with said feeding rollers, a handle connected with said shaft for rotating the same, a ratchet wheel rigidly secured to said gear, a pawl carrier rigidly secured to said shaft, a pawl carried by said pawl carrier and engaging said ratchet wheel, a normally inoperative means for separating said feeding rollers, an actuating member connected with said separating means, a part connected with said shaft and arranged to engage said actuating means and move said separating means to its operative position when a predetermined movement has been imparted to said handle, other means connected with said shaft to cause said actuating device to move said separating means to an inoperative position 80 85 90 when said operating handle is moved in a reverse direction, a guide for said web so arranged that a crease between adjacent sections of said web will be in engagement therewith when said separating means is moved to its operative position and the resiliency of said web will move the same rearwardly when said rollers have been separated, and means to limit the rearward movement of said web. 95

3. In an autographic register comprising a structure adapted to support a web of paper which is folded into superimposed sections of equal length, a pair of feeding rollers one of which is movable toward and from the other, a shaft, a gear rotatably mounted on said shaft and operatively connected with said feeding rollers, a handle connected with said shaft for rotating the same, a ratchet wheel rigidly secured to said gear, a pawl carrier rigidly secured to said shaft, a pawl carried by said pawl carrier and engaging said ratchet wheel, tapered members arranged to be moved between said rollers and separate the same, an arm rotatably mounted on said shaft and connected with said tapered members, a plate rigidly secured to said shaft, stops carried by said plate and arranged on opposite sides of said arm and so arranged that one of said stops will engage said arm and move said tapered mem- 100 105 110 115 120 125 130

- bers into operative engagement with said rollers when a predetermined movement has been imparted to said operating handle and the other of said stops will engage said arm 5 and retract said tapered members when said operating handle is moved in the other direction, a guide for said web so arranged that a crease between adjacent sections of said web will be in engagement therewith 10 when said rollers are separated, thereby permitting said web to move rearwardly, and means for limiting the rearward movement of said web.
4. In an autographic register comprising 15 a structure adapted to support a web of paper which is folded into superimposed sections of equal length, feeding members to engage said web, an operating device having movement in two directions, means controlled by 20 the movement of the operating device in one direction to impart feeding movement to the feeding members, means to release said web from said feeding members at the end of said feeding movement, and means controlled by 25 the movement of said operating device in the other direction to cause said feeding members to engage said web.
5. In an autographic register comprising 30 a structure adapted to support a web of paper which is folded into superimposed sections of equal length, feeding members to engage said web, means arranged beyond said feeding members for severing said web, an operating device having movement in two directions, means controlled by the movement of said operating device in one direction to impart feeding movement to said feeding members, a guide 35 so arranged that a creased portion of said web will project to the rear thereof as said web passes about the same, means actuated by said projecting portion of said web for causing said web to be released by said feeding members, and means controlled by the movement of said operating device in the other direction to cause said feeding members to engage said web.
- 45 6. In an autographic register comprising a structure adapted to support a web of paper which is folded into superimposed sections of equal length, feeding rollers to engage said web, means to separate said feeding rollers to release said web, an operating device, means comprising a one-way clutch to connect said operating device with said feeding rollers when said operating device is moved in one direction, means for actuating said 50 separating means, and means controlled by the movement of said operating device in the other direction to retract said separating means.
7. In an autographic register comprising 55 a structure adapted to support a web of paper which is folded into superimposed sections of equal length, feeding members to engage said web, an operating device having movement in two directions, means controlled by 60 the movement of the operating device in
- one direction to impart feeding movement to the feeding members, means controlled by a crease between adjacent sections of said web for releasing said web from said feeding members at the end of said feeding movement, and means controlled by the movement of said operating device in the other direction to cause said feeding members to again engage said web. 70
8. In an autographic register comprising 75 a structure adapted to support a web of paper which is folded into superimposed sections of equal length, feeding rollers to engage said web, means to separate said feeding rollers to release said web, an operating device, means comprising a one-way clutch to connect said operating device with said feeding rollers when said operating device is moved in one direction, means controlled by a crease between adjacent sections of said web to cause said separating means to release said web, and means controlled by the movement of said operating device in the other direction to retract said separating means. 80
9. In an autographic register comprising 85 a structure adapted to support a web of paper which is folded into superimposed sections of equal length, feeding members to engage said web, an operating device having movement in two directions, means controlled by the movement of said operating device in one direction to impart feeding movement to said feeding members, a guide 90 so arranged that a creased portion of said web will project to the rear thereof as said web passes about the same, means actuated by said projecting portion of said web for causing said web to be released by said feeding members, and means controlled by the movement of said operating device in the other direction to cause said feeding members to engage said web. 95
10. In an autographic register comprising 100 a structure adapted to support a web of paper folded into superimposed sections of equal length, feeding rollers to engage said web, tapered members arranged to be engaged by parts of said rollers and moved between the same to separate said rollers and release said web, an operating device having movement in one direction to impart feeding movement to said feeding members, a guide so arranged that a creased portion of said web will project to the rear thereof as said web passes about the same, a movable member arranged to be engaged and actuated by the projecting portion of said web, means for connecting said movable member with said tapered members to cause the latter to be moved into frictional engagement with said rollers, and means actuated by said operating device to retract said tapered members. 105
11. In an autographic register comprising 110 a structure adapted to support a web of paper folded into superimposed sections of equal length, feeding rollers to engage said web, tapered members arranged to be engaged by parts of said rollers and moved between the same to separate said rollers and release said web, an operating device having movement in one direction to impart feeding movement to said feeding members, a guide so arranged that a creased portion of said web will project to the rear thereof as said web passes about the same, a movable member arranged to be engaged and actuated by the projecting portion of said web, means for connecting said movable member with said tapered members to cause the latter to be moved into frictional engagement with said rollers, and means actuated by said operating device to retract said tapered members. 115
12. In an autographic register comprising 120 a structure adapted to support a web of paper folded into superimposed sections of equal length, feeding rollers to engage said web, tapered members arranged to be engaged by parts of said rollers and moved between the same to separate said rollers and release said web, an operating device having movement in one direction to impart feeding movement to said feeding members, a guide so arranged that a creased portion of said web will project to the rear thereof as said web passes about the same, a movable member arranged to be engaged and actuated by the projecting portion of said web, means for connecting said movable member with said tapered members to cause the latter to be moved into frictional engagement with said rollers, and means actuated by said operating device to retract said tapered members. 125
13. In an autographic register comprising 129 a structure adapted to support a web of paper folded into superimposed sections of equal length, feeding rollers to engage said web, tapered members arranged to be engaged by parts of said rollers and moved between the same to separate said rollers and release said web, an operating device having movement in one direction to impart feeding movement to said feeding members, a guide so arranged that a creased portion of said web will project to the rear thereof as said web passes about the same, a movable member arranged to be engaged and actuated by the projecting portion of said web, means for connecting said movable member with said tapered members to cause the latter to be moved into frictional engagement with said rollers, and means actuated by said operating device to retract said tapered members. 133

a structure adapted to support a web of paper folded into superimposed sections of equal length, feeding mechanism comprising an operating device to advance said web, 5 means to release said web from said feeding means, a guide spaced at the rear of said feeding means and so arranged that a creased portion of said web will project to the rear of said guide as said web passes about the same, a movable device operatively connected with said releasing means and having a part so arranged with relation to said guide that it will be engaged by the projecting portion of said web and cause said releasing 10 means to be actuated and will control the position of said web after it has been released. 15 12. In an autographic register comprising a structure adapted to support a web of paper which is folded into superimposed sections of equal length, feeding rollers to engage said web, a severing device arranged beyond said feeding rollers, an operating device, means including a one-way clutch to connect said operating device with said feeding rollers when said operating device is moved in one direction, means for separating said feeding rollers to release said web, means controlled by a crease between adjacent sections of said web to position the 20 same with relation to said severing means when said web has been released by said rollers, and means controlled by the movement of said operating device to retract said separating means and cause said rollers to 25 again engage said web. 30 35 13. In an autographic register comprising a structure adapted to support a web of paper which is folded into superimposed sections of equal length, a writing table, means to feed said web over said writing table and successively discharge the web sections from the register, means to actuate said feeding means, a web severing device arranged beyond said feeding means, means 40 controlled by said actuating device to release said web from said feeding means, a guide for said web held against bodily movement lengthwise of said web and so arranged that a crease between adjacent sections of said 45 web will be in engagement with said guide at the end of each feeding operation and that said web will move rearwardly with relation to said writing table and said guide when the web has been released from said feeding 50 means, and means cooperating with said creased portion to position said web with relation to said severing means. 55 60 65 14. In an autographic register comprising a structure adapted to support a web of paper which is folded into superimposed sections of equal length, a guide about which said web extends, means for advancing said web a predetermined distance and for releasing the same when a crease between adjacent sections thereof is in engagement with

said guide, a writing table over which said web moves, said guide being held against bodily movement lengthwise of said web and so arranged that the resiliency of said web will cause the creased portion thereof to move rearwardly with relation to said writing table and said guide when the web has been released, and means cooperating with said creased portion to determine the final position of said web. 70 75

15. In an autographic register comprising a structure adapted to support a web of paper which is folded into superimposed sections of equal length, a writing table over which said web moves a guide about which said web extends, feeding members, a web severing device arranged beyond said feeding members, means for actuating said feeding members to move said web a predetermined distance, to move one of said feeding members to an inoperative position to release said web and to then cause said feeding member to be restored to its operative position, said guide being held against bodily movement lengthwise of said web and so arranged that at the end of each feeding operation a crease between adjacent portions of said web will be in engagement with said guide and the resiliency of said web will move the same rearwardly with relation to said writing table and said guide when it has been released from said feeding members, and means cooperating with said creased portion to limit the resilient movement thereof and to position the web with relation to said severing device. 80 85 90 95 100

16. In an autographic register comprising a structure adapted to support a web of paper which is folded in superimposed sections of equal length, a writing table over which said web moves feeding rollers, means for actuating said feeding rollers to advance said web a predetermined distance, a guide for said web held against bodily movement lengthwise of said web and so arranged that at the end of said feeding movement a crease in said web will be in contact with said guide, means for releasing said web from said feeding rollers at the end of said feeding movement, means for so supporting said web with relation to said guide that the resiliency of said web will cause the same to move rearwardly with relation to said writing table and said guide when it has been released by said feeding rollers, means to limit the rearward movement of said web, and means for causing said feeding rollers to again grip said web. 105 110 115 120

17. In an autographic register comprising a structure adapted to support a web of paper which is folded into superimposed sections of equal length, a writing table over which said web moves feeding rollers to advance said web, operating mechanism including a handle, and means for causing the 125 130

movement of said handle in one direction to first actuate said rollers to advance the web a predetermined distance and to then move one of said rollers to an inoperative position, 5 a guide for said web so arranged that at the end of said feeding movement a crease in said web will be in engagement with said guide, means for so supporting said web with relation to said guide that the resiliency of 10 said web will move the same rearwardly with relation to said writing table when it is released by said rollers, means to limit the rearward movement of said web, and means actuated by the movement of said operating 15 handle in a reverse direction to restore said feeding roller to its operative position.

18. In an apparatus of the character described, comprising a structure adapted to support a plurality of superimposed webs 20 of paper which are folded in sections of equal length, and a writing table over which the several sections of said superimposed webs are successively moved, means for advancing said webs a predetermined distance and then 25 releasing the same, a guide mounted at the rear of said writing table and about which said superimposed webs pass, said guide being held against bodily movement lengthwise of said web and so arranged and of such a character that creased portions of said web will 30 be supported thereby when said webs are released and the resiliency of said webs will move the same rearwardly with relation to said writing table and said guide and cause 35 the creases in the inner webs to enter the creases in the outer webs and thereby maintain said webs in alinement.

19. In an apparatus of the character described, comprising a structure adapted to 40 support a plurality of superimposed webs of paper which are folded in sections of equal length, and a writing table over which the several sections of said superimposed webs are successively moved, means to advance said 45 webs a predetermined distance and then release the same, a guide mounted to the rear of said writing table, held against bodily movement lengthwise of said web and so arranged that creased portions of said webs will be 50 supported thereby at the end of each advancing operation and said webs will move rearwardly with relation to said writing table and said guide due to their resiliency when they have been released, and means arranged 55 adjacent to said guide to cause said webs to bend sharply about the same.

20. In an autographic register comprising a structure adapted to support a web of paper which is folded into superimposed sections of 60 equal length, a writing table over which said web moves, a guide about which said web extends, feeding members acting on said web, operating mechanism to cause said feeding members to advance said web a predetermined distance, to then move one of said

members out of engagement with said web and to subsequently cause said feeding member to be restored to its operative position, 70 said guide being held against bodily movement lengthwise of said web and so arranged that the resiliency of said web will cause the same to move rearwardly with relation to said writing table and said guide when said feeding roller is in its inoperative position, and a part spaced from said guide to control the resilient movement of said web.

In testimony whereof, I affix my signature hereto.

PHILIP A. JACKSON.
